Primary Examiner — Rhea Shields(74) *Attorney, Agent, or Firm* — Birch, Stewart, Kolasch & Birch, LLP(57) **CLAIM**

The ornamental design for a sealing cap, as shown and described.

DESCRIPTION

1. Sealing cap
- 1.1 : Perspective
- 1.2 : Front
- 1.3 : Back
- 1.4 : Left
- 1.5 : Right
- 1.6 : Top
- 1.7 : Bottom
- 1.8 : Bottom perspective view
- 1.9 : Cross-sectional
- 1.10 : Reference

1 Claim, 10 Drawing Sheets(56)
